FEEDING MECHANISM FOR ROCK DRILLS

John C. Curtis, Garfield Heights, Ohio, assignor
to The Cleveland Rock Drill Company, Cleve-
land, Ohio, a corporation of Ohio

Application November 29, 1935, Serial No. 52,135

23 Claims. (Cl. 121—9)

This invention relates broadly to rock drills, but more particularly to feeding mechanism for rock drills of the percussive type wherein the drill is slidably mounted on a suitable support 5 or shell, and is automatically fed toward or away from the work.

One object of this invention is to provide a rock drill with a new and efficient feeding mechanism capable of feeding the rock drill toward or away from the work.

Another object of this invention is to produce a feeding mechanism for rock drill whereby the latter is capable of relatively long feed toward or away from the work, without increasing the 15 overall length of the assembly.

Another object of this invention is to utilize the force of the jars imparted to the rock drill due to the reversal of the piston strokes therein, for feeding the rock drill in either direction.

Other objects more or less ancillary to the foregoing and the manner in which the various objects are attained, reside in the specific construction and aggroupment of the elements peculiar to this structure, as will become apparent from a more complete examination of this specification, in the claims of which there are assembled certain specific combinations of parts and specific constructions indicative of the scope and spirit of the invention.

In the drawings which illustrate a preferred 30 form of the invention:

Fig. 1 is a side elevational view of a rock drill having the invention applied thereto, the support being shown in section to illustrate details of construction.

Fig. 2 is an enlarged cross sectional view taken 35 in a plane indicated by line 2—2 in Fig. 1.

Fig. 3 is an enlarged cross sectional view taken in a plane indicated by line 3—3 in Fig. 1.

Fig. 4 is a fragmental longitudinal sectional view taken in a plane indicated by line 4—4 in Fig. 2.

Fig. 5 is a view similar to Fig. 4 illustrating a portion of the mechanism shown in the latter 45 with some parts shown in different position.

Fig. 6 is a cross sectional view taken in a plane indicated by line 6—6 in Fig. 4.

Fig. 7 represents a portion of the mechanism 50 illustrated in Fig. 4, with the valve shown in different position.

Fig. 8 is a cross sectional view taken in a plane indicated by line 8—8 in Fig. 4.

Fig. 9 is a top plan view of the portion of the 55 mechanism shown in Fig. 4.

Fig. 10 is a cross sectional view taken in a plane indicated by line 10—10 in Fig. 3.

Fig. 11 is a cross sectional view taken in a plane indicated by line 11—11 in Fig. 3.

Fig. 12 is an enlarged cross sectional view taken 5 in a plane indicated by line 12—12 in Fig. 4.

Fig. 13 is a cross sectional view taken in a plane indicated by line 13—13 in Fig. 4.

Fig. 14 is an enlarged sectional view taken in a plane indicated by line 14—14 in Fig. 4.

Referring to the drawings, 15 represents a rock 10 drill or drilling motor of the fluid actuated percussive type which is slidably mounted within

guideways 16 formed in the upper end of the side walls of a shell or support 17. Transversely 15 disposed through the back head 18 of the motor 15, there is a cylindrical bore 19 having a throttle valve 20 rotatable therein by the medium of a handle 21. To one end of the bore 19 is detachably affixed a motive fluid connection 22 through 20 which motive fluid may be admitted into a motive fluid chamber 23 formed within the throttle valve 20. Leading from the chamber 23 to the peripheral wall of the throttle valve 20, there are two radially disposed ports 24 and 25, which are capable of communication with a passage 26 formed in the head 18 for admitting motive fluid into the motor 15. Closer to the free end of the throttle valve, the latter is provided with a groove 27 extending partly around the throttle valve. This groove is in constant communication with the chamber 23 through a radially disposed port 28.

The back head 18 has also incorporated therein a valve mechanism comprising a valve casing 29 formed with a cylindrical bore 30 extending 35 therethrough and enlarged at one end to form a counterbore 31. Provided around the valve casing 29, there is a groove 32, which opens into the bottom of the counterbore 31 through small ports 33. Between its ends, the bore 30 is provided with an internal annular groove 34 in constant communication with a port 35. Opening into the extreme end of the bore 30, there is a small port 36 leading to the atmosphere through a port 37. Slidably mounted within the bore 30, there is a 40 valve 38 having a flange 39 slidable within the counterbore 31. The flange 39 is transversed by a plurality of small ports 40. Back of the valve casing 29, there is a plate 41 having a port 42 therethrough to afford communication of the 45 counterbore 31 with a cavity 43 formed within the head 18, and into which opens the port 35. The annular groove 32 formed around the valve casing 29 is in constant communication with the throttle valve 20 through a port 44, with which 50 55

the throttle valve groove 27 is capable of communication.

Secured to the back head 18 by the usual side bolts 45, there is a housing 46 having detachably secured thereto by bolts 47, a casing 48. Rotatably mounted within the housing 46 in coaxial alignment with the center axis of the drilling motor 15, there is a stem 49 formed with external splines 50. This stem extends into the 10 casing 48, where it is terminated by an enlargement or head 51, which is machined to pivotally receive two pawls 52, each having a spring 53 acting thereon and carried by the head 51. Surrounding the head 51, there 15 is a ring 54 rotatable within the casing 48. This ring has its inner wall machined to form ratchet teeth 55 with which the pawls 52 are engageable, while the external wall of the ring is machined to form teeth 56. Slidably disposed within the 20 casing 48 in transversal relation with the stem 49, there is a rack 57 with the teeth 58 thereof meshing the teeth 56 of the ring 54. This rack is also terminated by an enlarged cylindrical head 59, which is slidably mounted within a cylindrical chamber 60 formed in the casing 48, and 25 within which motive fluid may be admitted on one side of the head 59 through a port 61 leading from the cavity 43 provided in the back head 18 adjacent the valve casing 29. The chamber 60 is 30 also capable of communication with the atmosphere through a small vent 62. The rack 57 is constantly urged toward the left in Fig. 6 by a compression spring 63 interposed between the 35 end of the rack and the end of the bore within which it is disposed.

Mounted on the stem 49 in abutting relation with the head 59 of the former, there is a member or head 64 secured to the stem 49 against rotation by a key 65. The head 64 also carries 40 pivotally mounted pawls 66 having spring pressed plunger 67 acting thereon. Surrounding the head 64, there is a ring 68 having the inner wall thereof machined to form ratchet teeth 69 with which the pawls 66 engage. The external 45 wall of the ring 68 is formed with a notch 70 adapted to receive the end portion of a plunger 71 which is mounted within a bore 72 formed in the casing 48 in parallel alignment with the rack 57. This bore is closed by a plug 73 and has disposed therein a relatively heavy compression 50 spring 74 constantly urging the plunger 71 toward the left in Fig. 8.

Slidably mounted on the stem 49 there is a sleeve 75 formed with internal splines 76 meshing with the splines of the stem 49. Intermediate its ends, the sleeve 75 is provided with an external annular groove 77. The sleeve 75 has its right end portion in Fig. 4 terminated by external splines 78 capable of engagement with corresponding internal splines of a bevel gear 79 rotatably mounted in the housing 46 in coaxial alignment with the center axis of the stem 49. This bevel gear is hollowed, and has friction disks 80 disposed therein for engagement with the stationary back head 18. The other end portion of the sleeve 75 is similarly formed with external splines 81 capable of engagement with corresponding internal splines of a bevel gear 82 which 65 is rotatably mounted within the casing 48, and like the gear 79, has friction disks 83 disposed therein. Between the gear 82 and the ring 68, there is interposed a plate 84. The teeth of the bevel gear 79 and 82 are in constant interengagement with the teeth of a third bevel gear 85

mounted therebetween in a manner affording the shank 86 thereof to extend through the housing 46 between the side walls of the shell 17. To the portion of this shank protruding from the housing 46 is affixed by a key 87, a gear 88. 5

Secured to the top of the housing 46 by bolts 89, there is a cap 90 formed with a vertical bore adapted to rotatably receive the shank portion 91 of a handle 92, the latter extending horizontally above the housing 46. Depending from the 10 shank 91 of the handle 92 in eccentric relation with the center axis thereof, there is a pin 93 having a segment 94 loosely mounted thereon and extending into the annular groove 77 formed on the sleeve 75. To prevent accidental rotary movement of the handle 92, the peripheral wall of the shank 91 is machined to form a series of detents 95 adapted to receive the end of a spring pressed plunger 96 slidably mounted within the cap 90. 15

The free end portion of the casing 48 is formed with a screw threaded bore 97 adapted to accommodate a packing 98, washer 99 and the head 100 of a small tube 101. The bore 97 is closed by a plug 102 engaging the washer 99 to compress the packing 98 and assure a fluid tight 20 joint between the tube and housing 48. The tube 101 extends through the stem 49 and the back head 18 into the drilling motor 15, from where it extends into the drill steel in the usual manner for conveying cleansing fluid, such as water, 25 to the cutting edge of the drill steel. Adjacent the plug 102, the casing 48 is provided with a laterally projecting boss 103 which is internally threaded to receive a connection capable of admitting cleansing fluid into the bore 97, from 30 where it is free to flow through the tube 101 via ports 104 formed in the plug 102.

Rigidly secured to one side wall of the shell 17 by bolts 105, there is a rack 106 extending substantially the full length of the shell. The teeth 40 of this rack are in constant operative engagement with the teeth of the gear 87.

In the operation of the mechanism, the throttle valve 20 may be rotated in a clockwise direction in Fig. 10 sufficiently to bring the groove 27 45 in communication with the port 44. In this instance, the motive fluid admitted into the throttle valve chamber 23 through the motive fluid connection 22, will flow into the valve casing annular groove 32 through the throttle valve port 50 28, groove 27, port 44, from where it is free to flow into the valve casing counterbore 31, through the ports 33. The motive fluid acting on the right side of the valve flange in Fig. 7, will flow through the ports 40, to act on the left side of 55 the flange and maintain the valve in the position shown in Fig. 7. From the valve casing counterbore 31, the motive fluid is free to flow into the cavity 43 through the port 42, from where it is admitted into the cylindrical chamber 60 through 60 the port 61. Motive fluid acting on the left side of the rack head 59 in Fig. 6, will drive the rack 57 against the compression of the spring 63. When the head 59 uncovers the port or vent 62, the motive fluid acting on the head will exhaust to 65 the atmosphere, causing thereby a drop of pressure in the cylindrical chamber 60, and a consequential drop of pressure in the valve casing counterbore 31. Due to the pressure of the motive fluid acting on the right side of the valve 70 flange 40, the valve will shift in the position shown in Fig. 4, closing thereby the port 42, and permitting the motive fluid previously admitted into the cylindrical chamber 60 to exhaust therefrom via the port 61, cavity 43, port 35, an- 75

nular groove 34 and ports 36 and 37. The motive fluid now exhausting from the cylindrical chamber 60 will allow the rack 57, due to the effort of the compression spring 63, to return in 5 the position shown in Fig. 6. Simultaneously the motive fluid still admitted on the right side of the valve flange 39 through the ports 33, will flow through the ports 40 on the left side of the flange. Since the left side of the flange is of a 10 greater effective area than the right side thereof, the valve will again be shifted in the position shown in Fig. 7, thus readmitting motive fluid into the cylindrical chamber 60 through the port 61, for driving the rack 57 toward the right in Fig. 15. From the foregoing it will be understood that when motive fluid is admitted from the throttle valve 20 into the port 44, the rack 57 is automatically reciprocated, thus imparting an oscillatory motion to the ring 54 due to the engagement 20 of the rack teeth 58 with the teeth 56 of the ring 54. During the rotary motion of the ring 54 in a counterclockwise direction in Fig. 6, the pawls 52 engaging the ratchet teeth 55 will transmit the rotation of the ring to the stem 49, 25 and consequently to the head 64 secured to the stem by the key 64. In this instance, the pawls 66 carried by the head 64, will simply ride the ratchet teeth 69 of the ring 68, without transmitting rotation to the latter. During the rotation 30 of the ring 54 in a clockwise direction in Fig. 6, the pawls 52 carried by the head 51 of the stem 49, will simply ride the ratchet teeth 55 of the ring without imparting rotation in a clockwise direction to the stem 49, which rotation is 35 checked by the mechanism shown in Fig. 8. Referring to the latter, it will be seen that the pawls 66 carried by the head 64 keyed on the stem 49 and engaging the ratchet teeth 69, would transmit the rotary motion of the stem 49 in a clockwise direction to the ring 68. The rotation of the latter however is checked due to the interengagement of the spring pressed plunger 71 with the notch 70, affording thereby a cushion means for checking the rotation of the stem 49 in a 40 clockwise direction.

The rotation of the stem 49 in a counterclockwise direction is transmitted to the sleeve 75 due to the interengagement of the splines 76 thereof with the splines 50 of the stem. Assume now that 50 the sleeve 75 is to be positioned as shown in Fig. 4, that is, with the splines 76 thereof in engagement with the internal splines of the bevel gear 79. In this instance the rotation of the sleeve in a counterclockwise direction is transmitted 55 to the bevel gear 79, and therefrom to the bevel gear 80 in a clockwise direction. The gear 87 keyed on the shank of the gear 80, will also rotate in a clockwise direction and due to the engagement of the teeth thereof with the rack 106, will impart rearward feeding motion to the drilling motor 15. When it is desired to feed the drilling motor toward the work, the handle 92 may be rotated to cause the segment 94, mounted in eccentric relation with the center 60 axis of the shank handle 91, to shift the sleeve 75 in the position shown in Fig. 5. In this instance the splines 81 of the sleeve 75 engaging the splines of the bevel gear 82 will transmit rotation to the gear 87 in a counterclockwise direction. The gear 87 engaging the rack 106 will cause forward feeding motion of the drilling motor 15.

When it is desired to lock the drilling motor 15 against slidable movement relative to the shell 75 17, the handle 92 may be rotated to position the

sleeve 75 in equidistant relation with the bevel gears 79 and 82, causing thereby the engagement of the sleeve splines 78 with the splines of the bevel gear 79 and the similar engagement of the sleeve splines 81 with the bevel gear 82. In this 5 instance the rotation of the bevel gears 79 and 82 is prevented due to the engagement of the bevel gear 85, and since this gear is in engagement with the shell 17 through the gear 87 and rack 106, the drilling motor is locked against slidable 10 movement relative to the shell.

The speed of the forward or backward feeding motion of the drilling motor may be controlled by the operator applying pressure on the handle 92 to cause the forcible engagement of the end 15 of the sleeve 75 with either the friction disks 80 or 83, reducing thereby the speed of rotation of the sleeve, and the consequential speed of rotation of the gear 87.

When the throttle valve 20 is positioned to 20 cause the registration of the throttle valve port 25 with the port 26, the port 44 is closed by the throttle valve, and motive fluid is admitted into the drilling motor 15 for actuating the same, without actuating the feeding mechanism. During the actuation of the drilling motor, the jars resulting from the reciprocation of the hammer piston in the motor, will impart forward and backward slidable motion to the drilling motor relative to the shell 17. Due to the engagement 30 of the gear 87 with the rack 106, the former will tend to oscillate, thus tending to impart through the bevel gears and the sleeve 75, oscillatory motion to the stem 49. However, due to the mechanism illustrated in Fig. 8 associated with the stem 35 49, the latter is capable of rotation in only one direction, thus causing the jars imparted to the drilling motor 15 to effect the intermittent rotation in one direction of the gear 87, and permitting a step by step slidable feeding movement of the drilling motor in a corresponding direction. In this instance, the direction of feeding motion of the drilling motor may also be controlled by the handle 92 in the manner previously described.

As previously explained, the feeding mechanism is constructed and arranged in a manner whereby the water tube 101 is free to extend therethrough, thus permitting the plug 102 and water connection 103 to be located at the outer end of the casing 48. In this location, it is obvious that the plug 102 may readily be removed, and the water tube 101 replaced or inspected without necessitating the removal of a portion of the feeding mechanism.

Although the foregoing description is necessarily of a detailed character, in order to completely set forth the invention, it is to be understood that the specific terminology is not intended to be restrictive or confining, and it is to be further understood that various re-arrangements of parts and modification of structural detail may be resorted to without departing from the scope or spirit of the invention as herein claimed.

I claim:

1. In a feeding device for a rock drill, the combination with a support and a drilling motor slidably thereon, a feeding mechanism associated with said motor for imparting forward and backward feeding motion thereto, said mechanism including a rack longitudinally of said support, a gear rotatably carried by said motor in operative engagement with said rack, a power actuated unit included in said mechanism capable of rotation in a single direction, and rotation transmitting 75

means associated with said unit and gear operable for selectively controlling the direction of rotation of said gear for imparting forward or backward feeding motion to said motor due to 5 the operative engagement aforesaid.

2. In a feeding device for a rock drill, the combination with a support and a drilling motor slid- 10 able thereon, a feeding mechanism associated with said motor for imparting forward and back- 15 ward feeding motion thereto, said mechanism includ- 20 ing a toothed element longitudinally of said support, a member movably carried by said motor in operative engagement with the teeth of said element, a power actuated element capable of 25 movement in a single direction, and movement transmitting means between said last element and member operable for selectively controlling the 30 direction of movement of said member for im- parting forward or backward feeding motion to 35 said motor due to the operative engagement aforesaid.

3. In a feeding device for a rock drill, the combination with a support and a drilling motor slid- 40 able thereon, an elongated element longi- 45 tudinally of said support, a member carried by said drilling motor, said element and member having means formed thereon capable of inter- 50 engagement whereby the rotary motion of said member relative to said element causes the slid- 55 able movement of said drilling motor, a mech- 60 anism including a gear having a power actuated reciprocable rack associated therewith for im- 65 parting oscillatory motion thereto, a component 70 associated with said gear, means for transform- 75 ing the oscillatory motion of said gear into an 80 intermittent rotary motion of said component in 85 a single direction, and means for transmitting 90 the intermittent rotary motion of said component to said member in either direction, said last 95 means being operable for selectively controlling 100 the direction of rotation of said member, causing thereby the slidable movement of said drilling 105 motor in one or the other direction.

4. In a feeding device for a rock drill, the combination with a support and a drilling motor slid- 110 able thereon, an elongated element longitudinally of said support, a member carried by said motor, said element and member having means formed thereon capable of interengagement 115 whereby the rotary motion of said member relative to said element causes the slidable movement 120 of said drilling motor, a mechanism includ- 125 ing a gear having a power actuated reciprocable rack associated therewith for imparting oscil- 130 latory motion thereto, means for transforming 135 the oscillatory motion of said gear into an inter- 140 mittent rotary motion of said member in one 145 direction, and means operable for selectively con- 150 trolling the direction of rotation of said mem- 155 ber, causing thereby the slidable movement of 160 said motor in one or the other direction.

5. In a feeding device for a rock drill, the combination with a support and a drilling motor slid- 165 able thereon, an elongated element longi- 170 tudinally of said support, a rotatable member carried by said drilling motor, said element and member having means formed thereon capable of interengagement whereby the rotary motion of 175 said member relative to said element causes the slid- 180 able movement of said drilling motor, a mech- 185 anism associated with said member includ- 190 ing a power actuated reciprocable driving ele- 195 ment operatively connected with a rotatably 200 driven element for imparting oscillatory motion 205 thereto, means for transmitting the rotary mo-

tion of said driven element in one direction to 210 said rotary member in either direction irrespec- 215 tive of the rotary motion of said driven element in the other direction, and means operable for 220 selectively controlling the direction of rotation 225 of said rotary member, thereby controlling the 230 direction of the slidable movement of said drill- 235 ing motor.

6. In a feeding device for a rock drill, the combination with a support and a drilling motor 240 slidable thereon, a reciprocatory piston in the 245 motor imparting jars thereto tending to move the 250 motor in two directions relative to the support, a rack longitudinally of the support, a gear carried by said motor in operative engagement 255 with said rack, the jars resulting from movement 260 of said motor tending to cause the rotation of said gear in both directions due to its operative en- 265 gagement with said rack, a mechanism includ- 270 ing an element rotatable in a single direction, 275 and means whereby said gear may be connected 280 to said element for preventing the rotation of 285 said gear in one or the other direction, control- 290 ling thereby the direction of movement of said 295 motor relative to said support.

7. In a feeding device for a rock drill, the combination with a support and a drilling motor 300 slidable thereon, a reciprocatory hammer piston in the motor imparting jars thereto to move the 305 motor in two directions relative to the support, a movement resisting mechanism associated with 310 said motor for preventing the movement thereof in one direction, said mechanism includ- 315 ing a rack longitudinally of said support, a gear rotatable in both directions in operative engagement 320 with said rack, a member rotatable in a single 325 direction, and connection means between said 330 member and gear operable for selectively con- 335 trolling the direction of rotation of said gear, 340 controlling thereby the direction of movement of 345 said motor relative to said support.

8. In a feeding device for a rock drill, the combination with a support and a drilling motor 350 slidable thereon, a reciprocatory hammer piston in the motor imparting jars thereto tending to 355 move the motor in two directions relative to the 360 support, a rack longitudinally of the support, a gear carried by said motor in operative engage- 365 ment with said rack, the jars resulting from move- 370 ment of said motor tending to cause the rotation of 375 said gear in both directions due to its operative 380 engagement with said rack, a rotatable member 385 having a ratchet mechanism associated therewith 390 for preventing its rotation in one direction, and 395 means for operatively connecting said gear to 400 said member for transmitting the rotation of the 405 former in one direction to the latter and pre- 410 venting the rotation of said gear in the other 415 direction, controlling thereby the direction of 420 movement of said motor relative to said support.

9. In a feeding device for a rock drill, the combination with a support and a drilling motor slid- 425 able thereon, a reciprocatory hammer piston in the motor imparting jars thereto tending to move the 430 motor in two directions relative to the support, a rack longitudinally of the support, a gear carried by said motor in operative engagement with 435 said rack, the jars resulting from movement of 440 said motor tending to cause the rotation of said 445 gear in both directions due to its operative engage- 450 ment with said rack, a member rotatable in only 455 one direction, a duality of elements associated 460 with said gear alternatively connectable with said 465 member for transmitting the rotation of said gear 470 in either direction to said member in said one 475 direction.

direction, and means operable for selectively connecting one or the other of said elements with said member, controlling thereby the direction of rotation of said gear and the direction of movement of said motor relative to said support.

10. In a feeding device for a rock drill, the combination with a support and a drilling motor slidable thereon, a reciprocatory hammer piston in the motor imparting jars thereto to move the motor in two directions relative to the support, a movement resisting mechanism associated with said motor for preventing the movement thereof in one direction, said mechanism including a rack longitudinal of the support, a gear in operative engagement with said rack rotatable in either direction, a member rotatable in only one direction, and means for operatively connecting said gear to said member for selectively controlling the direction of rotation of said gear and the direction of movement of said motor relative to said support.

11. In a drilling apparatus, the combination with a support and a drilling motor slidable thereon, a reciprocatory hammer piston in the motor imparting jars thereto to move the motor in two directions relative to the support, and a movement resisting mechanism associated with said motor, said mechanism including a rack longitudinal of the support, a pinion in operative engagement with said rack rotatable in both directions due to the movement of said motor in two directions, gears associated with said pinion normally rotated thereby, and means for locking said gears against rotation, preventing thereby the rotation of said pinion and the movement of said motor relative to said support.

12. In a feeding device for a rock drill, the combination with a support and a drilling motor slidable thereon, a feeding mechanism associated with said motor for imparting forward and backward feeding motion thereto, said mechanism including a rack longitudinal of said support, a gear rotatably carried by said motor in operative engagement with said rack, a power actuated element rotatable in a single direction, transmission means between said element and gear including a member selectively movable in one position for transmitting the rotation of said element to said gear in one direction and in another position for transmitting the rotation aforesaid to said gear in the other direction, controlling thereby the direction of feeding motion of said motor.

13. In a feeding device for a rock drill, the combination with a support having a drilling motor slidable thereon, of a feeding mechanism for said motor including a single rack longitudinal of the support, a gear meshing said rack in a manner whereby the rotation thereof causes the feeding motion of said drilling motor, means for imparting rotation to said gear in either direction including a fluid actuated non-reversible motor, and connectable means between said last motor and gear whereby rotation in either direction may be transmitted to said gear.

14. In a feeding device for a rock drill, the combination with a support having a drilling motor slidable thereon, of a feeding mechanism for said motor including a single rack longitudinal of the support, a gear meshing with said rack in a manner whereby the rotation thereof causes the feeding motion of said drilling motor, means for imparting rotation to said gear in either direction including a fluid actuated non-reversible motor, clutch means between said last motor and gear whereby rotation in either direction may be trans-

mitted to said gear, and means for preventing the rotation of said gear in a direction adverse to that of the rotation transmitted thereto by said clutch means, preventing thereby the feeding motion of said drilling motor in a direction adverse to that of its feeding motion.

15. In a feeding device for a rock drill, the combination with a support having a drilling motor slidable thereon, of a feeding mechanism for said motor including a single rack longitudinal of the support, a gear meshing with said rack in a manner whereby the rotation thereof causes the feeding motion of said drilling motor, means for imparting rotation to said gear in either direction including a power actuated element rotatable in one direction, rotation resisting means associated with said element for preventing the rotation thereof in the other direction, and rotation transmitting means between said element and gear for transmitting the rotation of the former to the latter in either direction, said rotation resisting means preventing the rotation of said gear in a direction adverse to that of the rotation normally transmitting thereto by said rotation transmitting means, preventing thereby the movement of said drilling motor in a direction adverse to that of its feeding motion.

16. In a feeding device for a rock drill, the combination with a support having a rock drill slidable thereon, of a feeding mechanism for said rock drill including a single rack longitudinal of the support, a gear engaging said rack in a manner whereby the rotation thereof causes the feeding motion of said rock drill, means for imparting rotation to said gear in either direction including a fluid actuated non-reversible motor, rotation transmitting means between said motor and gear for transmitting the rotation of the former to the latter in either direction, a throttle valve for controlling the inlet of motive fluid into said motor, and means independent of the amount of pressure fluid admitted into said motor operable for selectively reducing the rotation speed of said gear.

17. In a feeding device for a rock drill, the combination with a support having a rock drill slidable thereon, of a feeding mechanism for said rock drill including a single rack longitudinal of the support, a gear engaging said rack in a manner whereby the rotation thereof causes the feeding motion of said rock drill, means for imparting rotation to said gear in either direction including a fluid actuated motor, rotation transmitting means between said motor and gear, a handle operable for selectively controlling the direction of rotation of said gear, and means selectively operable upon movement of said handle and independently of said motor for reducing the speed of rotation of said gear.

18. In a feeding mechanism for a rock drill, the combination with a support and a drilling motor slidable thereon in either direction, a duality of elements one carried by the motor and the other longitudinal of the support, interengageable means on said elements whereby the movement of one element relative to the other causes the slidable movement of the motor on the support, a power actuated member normally movable in two directions, and means for transmitting motion from said member to one of said elements in a selective direction for effecting the slidable movement of said motor in one or the other direction.

19. In a rock drill, the combination with a support and a drilling motor slidable thereon, a gear

- carried by the motor meshing with a rack carried by the support for causing the slideable movement of the motor upon rotation of the gear, a power actuated element rotatable in a single direction, and connectable means between said element and gear whereby rotation may be imparted to the latter for effecting the slideable movement of the motor in either direction.
20. In a feeding device for a rock drill, the combination with a support and a drilling motor slideable thereon, a reciprocatory piston in the motor imparting jars thereto to move the motor in two directions relative to the support, a duality of elements one carried by the motor for movement therewith and the other longitudinally of the support, interengaging means on said elements whereby the movement of the motor causes the rotation of the element carried thereby, a mechanism including a member rotatable in a single direction, and means whereby said last element may be connected to said member for preventing the rotation of the element in one or the other direction, controlling thereby the direction of movement of said motor relative to said support.
21. In a rock drill, the combination with a support and a drilling motor slideable thereon, a reciprocatory piston in the motor imparting jars thereto to move the motor in two directions relative to the support, of a movement resisting mechanism including an element normally rotatable in both directions due to the jars of the motor, a member rotatable in a single direction,

and means whereby said element may be connected to said member for preventing the rotation of the former in one or the other direction, controlling thereby the direction of movement of said motor relative to the support. 5

22. In a feeding device for a rock drill, the combination with a support having a drilling motor slideable thereon, a reciprocatory piston in the motor imparting jars thereto for normally moving the motor in two directions relative to the support, of a mechanism for controlling the direction of movement of the motor including a rack and a gear meshing with the rack for rotation relative thereto in two directions due to the jars of the motor, and a member rotatable in a single 15 direction connectable with said gear for selectively controlling the direction of rotation of the latter.

23. In a feeding device for a rock drill, the combination with a support having a drilling motor slideable thereon, of a feeding mechanism for said 20 motor including a duality of interengaging elements between said motor and support with one element rotatable relatively to the other for effecting the slideable movement of the motor, and means for imparting rotation to said rotatable element in either direction including a fluid actuated nonreversible motor selectively connectable with said rotatable element for imparting rotation thereto in either direction, effecting thereby the forward or backward feeding movement of the 25 motor.
